CLAIM

The ornamental design for a device holder as shown and described.

DESCRIPTION

FIG. 1 is a top, right side perspective view of a device holder showing our new design;

FIG. 2 is a front, left perspective view thereof;

FIG. 3 is a bottom, right perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The dashed-dot lines form the boundary of the claimed design and the even broken lines shown in the drawings are included for the purpose of illustrating portions of the device holder that form no part of the claimed design.

1 Claim, 9 Drawing Sheets
